UNITED STATES PATENT OFFICE.

SAMUEL ROE PAYNE, OF RIDDLERON, TENNESSEE.

BED-BRACE.

SPECIFICATION forming part of Letters Patent No. 595,201, dated December 7, 1897.

Application filed September 19, 1896. Serial No. 606,433. (No model.)

To all whom it may concern:

Be it known that I, SAMUEL ROE PAYNE, of Riddleton, in the county of Smith and State of Tennessee, have invented an Improved Bed-Brace, of which the following is a specification.

The present invention relates to a device for tightening the braces used in connection with bedsteads, &c.

With this object in view the invention consists of the details of construction and arrangement, which will be more fully described hereinafter.

In the accompanying drawings, which form a part of this application, Figure 1 is a plan view of the device in operating position. Fig. 2 is a side view of the tension device. Fig. 3 is a vertical central sectional view of the same. Fig. 4 is a reverse plan view.

Like letters of reference indicate corresponding parts in the several views.

Referring to the drawings, A represents a bedstead of the ordinary construction, comprising the head and foot and side rails. A staple or hook is secured in each end post, and adjacent thereto are the staples C, driven into the side rails. The brace-wires D D are attached to the hooks or pins B and pass through the staples C and extend diagonally across the bed-frame, crossing each other at the center, all of which is constructed in accordance with my Patent No. 531,641, granted January 1, 1895.

E represents a casting-piece centrally apertured at a and provided with peripheral ratchet-teeth b and downwardly-projecting guide-lugs c.

A circular disk F, having the lever-handle f attached thereto and having the hub g projecting downwardly therefrom, is provided for tightening the brace-wires D D, the said disk being placed into the casting-piece E and the hub g projecting down through the

aperture a. Projecting downwardly from the hub g are pins i for engaging with the said brace-wires. A pawl j is provided to engage with the peripheral ratchet-teeth b to prevent slipping of the tension device when turned. The said pawl works in the guideways k, situated on the under side of the lever-handle, and has the spiral spring m for keeping the said pawl in engagement. The said tension device is placed under the said stay-wires at their point of crossing, passing at right angles through the pins i and under the said guide-lugs, as shown. When it is desired to tighten the brace-wires, the hand-lever is moved around in the direction indicated by the arrow. The lever as it moves around is held by the pawl fitting into the ratchet-teeth and so the wires can be made taut.

Having thus described my invention, what I claim, and desire to secure by Letters Patent, is—

The combination with the end and foot boards and the side rails of a bedstead, of the end posts thereto, the hooks B B secured in said end posts, the staples C C fixed to said side rails near said end posts, the crossed brace-wires D D, detachably secured to said hooks and staples, the casting-piece E, provided with a central bearing-orifice a, circumferential ratchet-teeth b, and lateral guide-lugs c, the disk F provided with the integral lever-handle f, the concentric hub g, provided with the lateral pins i i and a spring-actuated pawl mounted in said handle and adapted to engage the teeth on the casting-piece E, substantially as shown and described.

In testimony whereof I affix my signature in the presence of two witnesses.

SAMUEL ROE PAYNE.
